UNITED STATES PATENT OFFICE

148,024

DESIGN FOR A RAILWAY CAR BODY

Basil E. Jones, Flossmoor, Ill., assigner to The
Pullman Company, Chicago, Ill., a corporation
of Illinois

Application December 22, 1945, Serial No. 124,982

Term of patent 14 years

(Cl. D66—1)

To all whom it may concern:

Be it known that I, Basil E. Jones, a citizen of the United States, residing at Flossmoor, in the county of Cook and State of Illinois, have invented a new, original, and ornamental Design for Railway Car Body, of which the following is a specification, reference being had to the accompanying drawings, forming part thereof.

In the drawings:

Fig. 1 is a general perspective view of a double bedroom in the railway car body of my new design and having certain portions broken away to afford a better illustration of the interior;

Fig. 2 is a horizontal mid-sectional view taken through the double bedroom;

Fig. 3 is a vertical transverse sectional view through the room taken on the line 3—3 of Fig. 2;

Fig. 4 is also a vertical transverse sectional view through the room but looking in the opposite direction from Fig. 3;

Fig. 5 is a vertical longitudinal sectional view through the double bedroom taken on the line 5—5 of Fig. 2;

Fig. 6 is a vertical longitudinal sectional view through the bedroom similar to Fig. 5 but showing the door side of the room; and

Fig. 7 is a general perspective view of a conventional railway car body of the type in which

this new design is incorporated and having portions broken away to reveal the disposition of the double bedroom within the vehicle and showing the supporting trucks in dotted lines.

The characteristic features of the present design reside in the bedroom interior design shown in the drawings.

I claim:

The ornamental design for a railway car body, substantially as shown and described.

BASIL E. JONES.
